Harry Radzinsky

UNITED STATES PATENT OFFICE

GEORGE H. PERRYMAN, OF TEANECK, NEW JERSEY, ASSIGNOR, BY MESNE ASSIGNMENTS, TO PERRYMAN ELECTRIC CO., INC., A CORPORATION OF DELAWARE

VACUUM TUBE

Application filed February 26, 1929. Serial No. 342,889.

This invention relates to an improvement in a vacuum tube of the thermionic type particularly adapted to radio purposes, and has for its object to provide a tube of this character in which the various internal elements 5 or parts of the tube structure will be strongly reinforced and braced so that the electrical characteristics of the tube will not be readily changed by the shifting of the parts of the tube relative to one another by reason of 10 rough handling, abuse in shipping or in general use.

A further object of this invention is to provide a strongly reinforced tube structure 15 of the character described in which the reinforcing or bracing elements will be so arranged and disposed relative to the other parts of the tube that these reinforcing or bracing elements will in no manner interfere 20 with the formation of a desirable and satisfactory vacuum in the tube.

I am aware that in tubes of the prior art, 25 an effort has been made to add rigidity to the tube structure by the use of bracing members of various kinds. In such instances, the brace members used were of such shape and dimension and were so disposed with respect to the tube elements, and particularly with respect to the anode or plate, that they prevented or else impeded the formation of a 30 satisfactory vacuum within the tube.

In most of the tubes of the prior art, the anode or plate member was of tubular form, and when brace members were used, the same 35 being placed across the top and bottom extremities of the plate, acted to effectively close the same. Thus, during the evacuation process, gases were trapped within the plate and the formation of a satisfactory vacuum within 40 the tube was prevented.

As heretofore stated, the object therefore of this invention is to provide a vacuum tube structure wherein a rigidly braced arrangement of the tube parts is provided, the design 45 and disposition of the brace members with respect to the other parts being such that the evacuation process is in no manner interfered with or impeded.

With these objects, and such other objects 50 as may hereinafter appear in view, I have

devised the particular arrangement of parts described below and more particularly pointed out in the claims appended hereto.

Reference is to be had to the accompanying drawings, forming a part hereof, in 55 which

Figure 1 is a front elevation of the tube structure, with the glass enclosing envelope omitted for clarity in illustration;

Figure 2 is a perspective view of one of 60 the brace members; and

Figure 3 is a view of the tube on the line 65 3-3 of Figure 1, looking in the direction of the arrows.

Throughout the various views of the drawing, similar reference characters designate 70 similar parts.

In the embodiment of my invention disclosed in the accompanying drawing, 1 indicates the conventional glass tube stem, the 75 upper end of which terminates in the usual press 2. Sealed within the press 2 and projecting upward therefrom are the filament leads 3 and 4 which connect to the opposite ends of the filament 5, said filament extending 80 upwardly and passing over hooked ends 6 formed on a pair of inverse springs 7, and thence extending downwardly to an anchorage member 19. The springs 7 are supported on the upper face of a brace member 8 which is preferably made of any suitable kind of 85 insulation.

Extending upwardly from the press 2, wherein its lower end is sealed, is a grid lead 9, which is welded, fused, or otherwise affixed to the lower end of one of the grid-supporting wires 10. A similar grid-supporting wire is shown at 11 and the same co-operates 90 with the wire 10 to effectively support the conventional type of wire grid 12. It will, of course, be understood that when a rectifying tube is made in accordance with my invention herein described, the grid may be omitted.

At 13 and 14 are the plate-supporting wires. 95 The same are secured at their lower ends to a metallic band or strap 15 which is securely held around the tube stem substantially as shown in the drawing, and the wire 14 is connected to a lead-in wire 20. These wires 13 100

and 14 extend upwardly to support the anode or plate member 16.

This plate member or anode 16 may be made of any suitable material such as sheet metal. I prefer, however, in carrying out my invention to use a finely-woven metallic mesh and have, in the accompanying drawing, shown the plate member 16 as being made of such material. It will be understood, however, that I do not limit my invention to the use of such material.

At 8 and 17 are shown the tube brace members. The same consist in a pair of flat narrow strips of insulation of sufficient body and thickness to securely hold the various parts of the tube structure in their proper relationship. These strips, one of which is disclosed in perspective in Figure 2 are flat, narrow elongated members and are each provided with a plurality of holes or apertures 18 to permit the various wires to pass through them. For instance the lower brace member 17 is perforated to permit the passage of the wires 10, 11, 13 and 14 as well as the filament anchorage wire 19, whilst the top brace member 8 is suitably perforated to permit the passage through it of the wires 11, 12, 13, 14 and the hooked spring terminals 6.

It is to be noted that the plate member 16 is firmly held between the brace members 8 and 17, the opposite ends thereof abutting against these members. The various wires passing through the spaced openings are effectively spaced from one another and are constantly maintained in such definite spaced relationship. Furthermore it will also be noted that these brace members are of substantially narrow width so that while the same rest securely against the upper and lower ends of the plate member 16 they do not close the open ends of the same (see Figure 3). The plate member being of greater transverse or cross sectional width than the width of these end braces, therefore has a large portion of its upper and lower open ends uncovered with the result that these braces do not act, as has been the case in prior structures, to trap gases within the plate structure, as such gases may freely pass out through the open upper and lower ends of the plate.

Furthermore, through the arrangement just disclosed, I find it unnecessary to cut away or perforate the plate as has in some types of prior tubes been done to aid in evacuating the tube.

Having described one embodiment of my invention, it is obvious that the same is not to be restricted thereto, but is broad enough to cover all structures coming within the scope of the annexed claims.

What I claim is:

1. In a vacuum tube, a filament and a tubular anode, brace members extending across the upper and lower ends of said anode and abutting against the same, said brace mem-

bers being of less width than the transverse width of the anode whereby a considerable portion of the upper and lower ends of said anode are uncovered by said brace members.

2. In a vacuum tube, plate-supporting, filament-supporting and grid-supporting wires, a pair of spaced narrow insulating strips perforated to permit the passage of said wires, a tubular plate of greater transverse width than the width of said strips, said strips being located at and abutting against the upper and lower ends of the plate and so disposed as to retain a considerable portion of the upper and lower ends of said plate in an uncovered or open condition.

Signed at the city, county, and State of New York, this 25th day of February, 1929.

G. H. PERRYMAN.
